BALL POINT PEN

Robert J. Burnham, Jamaica Estates, Long Island, N.Y.

Filed Feb. 4, 1960, Ser. No. 59,262

Term of patent 14 years

(Cl. D74—17)

FIG. 1 is a rear elevational view of the ball point pen embodying my new design;

FIG. 2 is a front elevational view thereof;

FIG. 3 is a side elevational view; and,

FIG. 4 is a top plan view of the ball pen shown in FIG. 2.

The dominant features of my design reside in the two integrally molded annular bands formed on the upper barrel portion in combination with two rectangular openings disposed beneath the forward portion of the clip, the lower opening allowing inward movement of the ball of the clip to effect retraction of the writing unit, and the upper opening being engaged by the latch portion of the plunger when the writing unit is retracted all as shown.

I claim:

The ornamental design for a ball point pen, as shown and described.
